Primary Examiner — Steven J Czyz(74) **Attorney, Agent, or Firm** — Matthew W. Mitchell(57) **CLAIM**

The ornamental design for a toy vehicle storage truck, as shown and described.

DESCRIPTION

FIG. 1 is a front perspective view of the toy vehicle storage truck of the present invention;

FIG. 2 is a left-side view thereof;

FIG. 3 is a right-side view thereof;

FIG. 4 is a front view thereof;

FIG. 5 is a top plan view thereof; and,

FIG. 6 is bottom plan view thereof.

The broken lines depict portions of the article that form no part of the claimed design.

1 Claim, 6 Drawing Sheets(56)
